SIGNAL DEVICE

Frederick B. Little, Chicago, Ill.

Application April 3, 1937, Serial No. 134,778

5 Claims. (Cl. 177—7)

This invention relates to improvements in audible signals and has special relation to an electrically operated audible signalling device which can be used in place of an ordinary electric door bell, or the audible signal of an alarm clock, or an electric signal to give information that a door has been opened, as well as in many other situations.

The invention contemplates the sounding of either a single sounding device, such as a musical tube, or the associated sounding of a series of sounding devices, such as a series of associated tubes which will produce a series of harmonious and related tones somewhat similar to the well known quarter hour audible signals of clocks, or metal bars with resonators.

An important feature of the invention relates to a simple form of construction of the striking hammer by which the sound produced may be readily adjusted as to strength, to the end that the tones produced may be of any strength from very soft to relatively loud.

Another important feature relates to a construction which, so far as the individual mechanical or sounding mechanism is concerned, includes duplicate parts, so that in making up a device for a specific purpose it is merely necessary to lengthen or shorten the longitudinal frame members to provide space for the number of individual striking units desired from one on up to such a multiple as may be necessary or desirable to produce the sequence or sequences of sounds or tones which may be required.

This construction readily lends itself to the production of a single tone or to a successive production of the same sequence of tones or to the production of different sequences of tones in a regular order.

Another feature, which aids materially in the reduction of cost of manufacturing the device, relates to the provision of end frame plates which are exact duplicates of each other, so that in manufacture the end plates can be produced from one set of dies and are all alike, and not rights and lefts, and can be used interchangeably at either end of the mechanism.

Another important feature relates to a simple means for protecting the mechanism from a continuous operation, which might occur when the control circuit is either accidentally or purposely held closed, for more than a time sufficient to start the mechanism into operation.

The preferred embodiment of the invention includes a self starting synchronized electric motor for operating the striking mechanism, a set of

chime tubes or metal bars with resonators and individual hammer or striking devices, one for each tube or bar, a low voltage relay control circuit for starting the motor and means for opening the motor circuit after the sounding of a 5 specified series of tones.

Another feature of the invention relates to a construction by which the mechanism can be associated with an alarm clock to be started by the usual alarm release, the arrangement being such 10 that the usual alarm release operates to close the motor circuit directly and not through the control circuit and the apparatus will then continue to sound until the motor circuit is opened by the operation of a hand switch.

For accomplishing the above and other advantages and objects, the invention consists in the means disclosed and particularly pointed out in the appended claims, the accompanying drawings forming part of this specification, and the 20 following description setting forth, in detail, but one of many possible embodiments of the invention, such disclosed arrangements, and combinations of parts, devices and mechanisms constituting, however, merely an exemplification of the 25 principle of the invention rather than a disclosure of the many modifications and variations which will readily suggest themselves to one skilled in the art.

The invention will be more readily understood 30 by reference to the accompanying drawings in which:—

Fig. 1 is a fragmentary front elevation of a mechanism including several musical tubes and embodying the invention in one, a preferred, 35 form;

Fig. 2 is a fragmentary vertical section on the line 2—2 of Fig. 3, and showing the operating mechanism in front elevation;

Fig. 3 is a fragmentary vertical section on the line 3—3 of Fig. 2;

Fig. 3a is a detail view similar to a part of Fig. 3 and showing same more clearly;

Figs. 4 and 5 are fragmentary horizontal sections on the lines 4—4 and 5—5 respectively of 45 Fig. 2;

Fig. 6 is a fragmentary vertical section on the line 6—6 of Fig. 5;

Fig. 7 is a fragmentary detail horizontal section 50 on the line 7—7 of Fig. 3;

Fig. 8 is a fragmentary vertical section on the line 8—8 of Fig. 2;

Fig. 9 is a fragmentary horizontal section on the lines 9—9 of Figs. 2 and 8;

Fig. 10 is a fragmentary side view of the apparatus showing an automatic motor stop;

Fig. 11 is a fragmentary detail vertical section on the line 11—11 of Fig. 2;

Fig. 12 is an elevational rear view of the mechanism of an electrically operated alarm clock, and showing the manner of applying a circuit closer to such a clock, to close the motor circuit;

Fig. 13 is a side elevation of one of the end plates of the frame;

Fig. 14 is a front elevation of one of the end plates;

Figs. 15 and 16 are horizontal sections on the lines 15—15 and 16—16 respectively of Fig. 13;

Fig. 17 is a detail side view of the hammer assembly similar to that shown in Fig. 8, but illustrating the means of varying the volume of sound produced;

Fig. 18 is a side view of the hammer stop;

Fig. 19 is a plan view of the hammer stop;

Fig. 20 is a side view of the hammer arm;

Fig. 21 is a plan view of the base of the hammer arm; and

Fig. 22 is an electric diagram showing the operating circuit and the control circuit and the several preferable ways of closing the control circuit.

As portrayed in Fig. 1, the apparatus is preferably arranged in a suitable case 30 which, as shown may carry a clock 31, with an extra hand 32 for indicating the time of operation of an alarm. The case, as shown, is adapted to be secured in an elevated position and I preferably provide a plurality of musical tubes 33 depending from the apparatus within the case.

Now referring to Fig. 2, the apparatus within the case will be described. In this figure the case 30 is represented merely by its top wall 34.

The apparatus within the case comprises several different mechanisms, all carried or mounted on a rigid frame designated generally by A.

The several devices or mechanism carried by the frame A, comprise, as shown, a multiple chime striking mechanism B, an electric motor 45 and operative connections C for operating the striking mechanism, a circuit controlling mechanism D operable on a low voltage circuit for starting the motor, and a protective device E, the function of which is to break or open the low voltage circuit should it happen that it inadvertently or intentionally remained closed for a period which would cause the operation of the signaling mechanism beyond a predetermined time or sequence of sound signals.

The frame A comprises two end plates 35 and 36, one at each end of the frame. These end plates are preferably die cast from a single die in order to reduce the cost and, although some features appear in each plate which are not used at one end, these features are made use of at the other end. Each end plate consists of a relatively wide vertical web part 37 which has an integral flange 38 on one vertical edge, the web 37 being arranged centrally of the flange. The flange 38 extends both above and below the web portion, as shown at 39 and 40. At the upper end 39 it is provided with a forwardly projecting end portion 41 by which the frame is secured to the case 30 by screw bolts 42, and at the lower end 40 it is provided with a forwardly projecting supporting lug 43 extending forward from the flange 38 and provided with a vertical central slot 44, (see Fig. 11,) elongated longitudinally of the lug for a purpose to be described. The upper extension of the end 75 39 of the flange is provided with a hole 45, see

Fig. 14, adapted to receive a supporting member, such as a screw, nail or hook, for supporting the mechanism on a wall or the like. The lug 43 at the lower end of the flange is positioned between the lower edge of the web 37 and the free lower end of the flange 38 and, like the upper end, this lower end portion of the flange is also provided with a hole 46 for receiving a suitable fastening device such as a screw 47.

As mentioned before, the two end plates are 10 exactly alike and are rigidly connected by a flat longitudinal bar 48 secured to the flanges 38 of the end members 35 and 36 by screws 49. This top bar 48 is provided with holes 50 which register with the holes 45 near the upper ends of the 15 flanges 38 of the end plates for receiving the supporting devices.

The end plates are also joined by a bottom bar 51 which rests on the tops of the lugs 43 and is secured thereto by bolts 43', one at each end, 20 which pass through the slots 44. The slots 44 permit the forward and rearward adjustment of the bar 51 for a purpose to be described. The end plates are further secured together by suitable spacer bars 51' to make the frame A very 25 rigid.

Chime striking mechanism

The chime striking mechanism B comprises a longitudinally extending horizontal shaft 52, which is rotatably mounted at its ends in bearing openings 53 provided in the end plates 35 and 36. The shaft is held against endwise movement by the hub of a chain sprocket 54 secured at one end of the shaft and by a set collar 54'. The chain sprocket 54 is located on the outer side of the frame plate 35 and the collar 54' on the inner side of said end plate. A timing cam 55 is secured on the opposite end of the shaft 52, outside of the opposite end frame 36.

Rigidly mounted on the shaft 52 between the end plates 35, 36 are striker disks 56, one for each chime tube to be struck.

The shaft 52 is located, as shown, about midway between the front and rear edges of the end plates, and below this shaft and toward the forward edges of the end plates is a second shaft 57 which is secured in horizontal position by screws 58 passing through holes 59 in the end plates and received in threaded holes in the ends of the shaft.

The hammer mechanisms, one for each tube to be struck, are mounted on this rigid shaft 57. Each of these hammer mechanisms consists of two main parts or members, a stop member 60 and a hammer member 61.

The stop member 60 comprises a yoke having two spaced arms 62 and a cross connecting part 63 joining the ends of the arms. The arms are provided with hubs 64 at their free inner ends which are provided with central holes 65 to fit snugly on the shaft 57. The yoke is adapted to be rigidly secured in place on the shaft 57, as by set screws 66, one in each hub.

The hammer member 61 comprises a hub 67 which fits between the inner faces of the hubs 64 of the stop member and has a central hole 68 to receive the shaft 57, the arrangement being such that the hammer member can swing freely on the shaft.

The hammer member 61 is provided with a arm 69 which is arranged to project out above the cross-part 63 of the stop member, and I interpose a yielding cushion 70 between these two parts, which yieldingly and quickly stops the hammer on its effecting stroke. Opposed to the pro-

jections 69 and extending substantially in the opposite direction is a curved cam projection 11, (see Fig. 17), the function of which will be described later.

5 The hammer member has a depending rigid hammer arm 72 which carries a flat spring-like strip 73 extending beyond the free end 74 of the hammer arm 72 and carrying a hammer head 75 secured rigidly thereon. The strip 73 lies substantially parallel to the hammer arm 72 and is secured at its inner end on a substantially radial shoulder 76 at the base of the arm 72, as with the screws 77. Between the outer end 74 of the hammer arm 72 and the spring strip 73 is arranged a cushion 78 of sponge rubber or the like to cushion the return or back movement of the hammer head. The hammer head itself comprises an inner end 79 and an outer end 80 secured on the free end of the strip 73 by means of 10 a central screw 81, the strip 73 being provided with a hole 82 through which the screw passes. The inner end 83 of the inner hammer part is provided with a central hole or pocket 84 which is internally screw threaded and which receives 15 and retains a soft plug 85, preferably made of leather or the like, which projects beyond the inner end of the part 79, and which constitutes the part of the hammer which contacts the sound producing device, which in the form shown 20 comprises one of the musical tubes or pipes 33.

The striker disks 56 on the shaft 52 are each provided with a circumferential row or ring of holes 87 to receive pins 88 spaced circumferentially around the disk 56 and the pins, which project 25 out sidewise from the disk are arranged and adapted to engage the curved cam projection 11 of the hammer and force the projection 11 downwardly and swing the hammer outwardly, as best shown in dotted lines on Fig. 8. The hammer is 30 yieldingly held inwardly, with the projection 89 in contact with the cushion 78 on the stop 60, by a coil spring 89 connected at one end on one of the frame rods 51' and at the other end secured to the hammer below the shaft 51, preferably to the inner end 91 of the strip 73, which is bent out at 35 right angles toward the rod 51' and is provided with a hole to receive the end of the spring.

The musical tubes 33 are hung from the lower cross bar 51 by non-resilient yokes 92, the bar 51, as best shown in Fig. 9, being provided with key-hole slots 93 in its front edge to receive the yokes 92. The slots 93 are spaced to cause the tubes 33 to hang in line with each hammer. This method of hanging the tubes leaves them practically free to vibrate in response to the strokes of the hammer.

The stop members 60 are adapted to be adjusted circumferentially on the fixed shaft 51 upon which they are mounted, and, as the tension springs 89 hold the projections 69 of the hammers pressed upon the stops 60, that is, upon the cushions 78, it will be evident that, by adjusting the stop members around the shaft 51, the spacing of the hammers from the tubes 33 can be adjusted.

As shown in Fig. 8, this spacing of the hammers from the tubes, as shown at 94, is usually about one eighth of an inch for the full or loudest tones and these tones can be softened to any practical amount by adjusting the stop members 60 so as to hold the hammers farther from the tubes when the hammers are at rest.

The hammer mechanism operates to swing the hammer outwardly for a stroke, as indicated in 5 dotted lines Fig. 8, against the force of the spring

89, and when the contacting pin 88 slips off of the cam projection 11 the spring 89 pulls the hammer inwardly to cause the stroke. However, the rigid hammer arm 61 is stopped on its inward movement by the stop 60, in its position shown in full lines in Fig. 8, but the hammer head 75 continues toward the tube 33, on account of being secured to the resilient strip 73, until it is stopped by hitting the tube, when it is instantly retracted, both by reason of the rebound and by the action of 10 the strip 73, which draws the hammer head back until the strip 73 contacts with the cushion 78.

As shown in Fig. 1, the several chime tubes 33 are of substantially uniform diameter, and to obtain the different tones desired these uniform diameter tubes vary in length. Sometimes it is desirable, instead of using tubes of uniform diameter, to use tubes known as graduated tubes, that is, tubes of different diameters, but the spaces at 94 should always be the same or uniform. By 15 means of the elongated slots 44 for the screws 43 which secure the bar 51 in position, the bar 51 can be adjusted in relation to the line of hammers to make the spaces 94 uniform for the several tubes in the set.

Such uniformity of spacing results in the tones produced by striking the several tubes being substantially uniform as to volume.

However, it is sometimes desired to reduce the volume and sound the tube softer than the loudest possible or to make it very soft. This is accomplished by adjusting the yoke 60 with the hammer stop 63 so as to stop or set the hammer at a distance from the tube in inverse ratio to the intensity of tone desired.

The multiplicity of holes 87 in the striker disks 56 are for the purpose of producing various combinations or sequences of sounds, as will be described more fully hereinafter.

The motor C, as has been described, is an electric motor preferably of the synchronized and self starting type, and it is associated with a suitable speed reducing mechanism shown generally at 86, which has a projecting driving shaft 97 which carries a chain sprocket 98. A driving 45 chain 99 connects this sprocket with the chain sprocket 54 on the shaft 52, on which the striker disks 56 are mounted, and when the motor is running the shaft 52 is rotated and the tubes 33 are struck in accordance with the setting or 50 arrangement of the pins 88 on the several disks 56.

It is obvious that the hammer arm with its resiliently mounted hammer and the yoke 60—62—63 constitute a hammer assembly which 55 can be manufactured in quantities and assembled, as may be necessary, with the shafts 65, one for each tube of the mechanism being made.

This arrangement greatly facilitates the manufacture of such chimes and reduces the manufacturing cost, as the hammer assemblies are all duplicates of each other. Furthermore, the adjustability of the yoke on the shaft does away with the necessity for varying the weight of the hammer heads to produce the volume of sound 65 desired.

Control mechanism

The control mechanism D functions preliminarily to close the motor circuit and thus start 70 the operation of the mechanism, by the closing of the control circuit by means of a push button or other means for temporarily closing the control circuit.

This mechanism includes a relay circuit closer, 75

designated generally by 100, and a circuit opener, which includes the timing wheel 55 and an associated pair of cooperating spring circuit closing and opening resilient contact strips 101—102.

5 The timing wheel 55 and the contact strips 101—102 are arranged on the outer side of the end plate 36, the wheel 55, which is secured rigidly on the outer end of the rotatable shaft 52, is made of insulation material such as hard 10 rubber, Bakelite or the like. The spring contact strips are metal, such as spring brass or bronze; they are secured rigidly on a block 103 of insulating material rigidly mounted on the outer side of the end plate 36 and project tangentially toward the timing wheel 55.

15 The timing wheel has a number of V-shaped notches 104 in its periphery, and the free end 105 of the contact strip 101 is formed to project into said notches when the wheel rotates to a position to permit same. The two strips 101 and 102 are provided with opposed and cooperating contact or circuit closing projections 106 and 107, respectively, and the arrangement is such that, when the free end 105 of the strip 101 enters 20 one of the notches 104 the contacts 106 and 107 are separated, thus opening the motor circuit in which these contacts are included, and when the wheel 55 is rotated sufficiently to lift the end 105 of the strip 101 out of a notch and cause it to 25 ride on the periphery of the wheel, the contact 106 is closed against the contact 107 and the motor circuit, of which these points are a part, is closed. The arrangement is such that, when the wheel 55 rotates to bring one of the notches 30 104 to a position to permit the end 105 of the strip 101 to enter the notch, the end 105 is forced into the notch by the resiliency of the strip and the notch is formed to permit the end 105 to drop 35 freely into the notch at such time. This causes 40 a quick break of the circuit at the points 106—107 and prevents sparking or burning of these points.

As shown, the wheel 55 has three of the notches 104 equally spaced around the periphery thereof and this construction serves to stop the shaft 45 52, three times in each revolution.

It should be understood that the striking pins 88 of the disks 56 are grouped in accordance with the number of notches 104, and consequently, as shown, the mechanism will produce three successive sequences of tones for each revolution of the shaft 52, which may be the same sequences, or different sequences in accordance with the arrangement of the pins 88.

The relay circuit closer 100 is arranged in a 55 low voltage circuit which may be preliminarily closed by means of an ordinary bell push button 108, (see Fig. 22) or by a door operated circuit closer 109, (see Fig. 22).

This relay circuit closer 100, as shown in the 60 drawings, comprises a fixed relay magnet 111 arranged to extend horizontally and rigidly mounted at one end on the upper end of a rigid L-shaped bracket 112, which is rigidly secured on a shelf 113 of insulating material arranged horizontally and rigidly secured on the inner side 65 of the end plate 36, as by screws 114.

There is a swinging armature 115 provided for the relay, which is L-shaped and is pivotally mounted to swing up and down on a pivot 116 carried by the bracket 112 below one end of the relay coil. The armature extends beneath the relay coil and has an upstanding arm 117 projecting in close proximity to the adjacent end 118 of the relay core, so that when the relay circuit 75 is closed the armature 115 will be swung

upwardly to the position shown in dotted lines Fig. 3 and when the circuit is opened it will drop by gravity to the position shown in full lines in said figure.

I make use of this movement of the relay armature to close the motor circuit. This is accomplished by the following means. Upstanding from the shelf 113 of insulation material are two opposed resilient contacts 119 and 120. These contacts are arranged in the motor circuit. Between these contacts 119 and 120 is arranged a cylindrical contact making member 121 rigidly carried on a horizontal rod 122, which in turn is rigidly secured to and projects laterally from the lower part of the armature 115. When the relay coil is energized and the armature 115 is 15 swung up, the member 121, which is in the form of a small cylinder, is drawn up between the opposed ends 123 and 124 of the contact members 119—120 and closes the motor circuit at this 20 point.

For the purpose of holding the motor circuit closed for a sufficient interval of time to start the apparatus into operation even though the starting circuit is but momentarily closed, I provide 25 a latch device 125, (see Figs. 3 and 22) to hold the circuit closing member 121 in circuit closing position between the contacts 119 and 120 for a certain predetermined interval of time. This latch device comprises a lever 126 arranged 30 on a horizontal pivot 127 between its ends and carried by the shelf 113. The upper end portion 128 of this lever has a notch 129 in one edge which is adapted to receive the rod 122 when the armature 115 is lifted, and the lever is swung 35 forward, to cause such operation, by a small tension spring 130 which is secured at one end to the upper end of the lever and at its opposite end to the shelf 113.

The spring 130 operates to hold the upper end 40 128 of the lever 126 toward the right (Fig. 3) at all times. In the normal open circuit position the upper part 128 of the lever 126 contacts with the rod 122 in position to be drawn forward beneath the rod when the armature 115 and the 45 circuit closure 121 are lifted, due to the energizing of the relay coil 111 by the closing of the auxiliary or starting circuit.

The normal standing or circuit open position is shown in full lines in Fig. 3a, which shows the 50 forward edge 131 of the latch lever 126 held against the rod 122 by the action of the spring 130.

After the armature 115 has been lifted by the energizing of the relay coil and the circuit closure 121 is locked in circuit closing position by the latch lever 126 the parts remain in this condition until the latch member is pulled back from engagement with the rod 122. To effect this release the lower end 132 of the latch lever 126 55 is engaged by a pin 133 set in one of the holes 87 in one of the disks 56 which is located below the control mechanism D.

The disks 56 are rotating in the direction of the arrow 134 on Fig. 3, and the lower end 132 of the 60 lever 126 projects into the path of the pin 133. The lever is preferably provided with an inclined camming edge 135 which is engaged by the pin, and, as the disk revolves, the pin swings the upper end 128 of the lever to the left, (Fig. 7 3,) and releases the rod 122, and then the armature drops down, if the control or starting circuit 7 is otherwise open, that is if the relay coil is not energized at this time.

The relation between the throw-off pin 133 and 8

the notches 104 in the motor circuit control disk 55 is such that when the apparatus is at rest it has been brought to rest by one of the notches 104 effecting the opening of the motor circuit 5 by the end 105 of the resilient switch arm 101 dropping into one of the notches 104, thereby separating the contacts 106 and 107. In the usual operation of the mechanism the motor circuit has been previously opened by the swinging 10 of the lever 126, thus letting the circuit closer 121 drop down out of contact with the contact strips 119 and 120. Then when the control circuit is again closed the motor circuit is first closed by the circuit closer 121, the circuit being open between the contacts 106 and 107 but before the release of the contact closer 121 takes place the disk 55 has rotated sufficiently to close the motor circuit at the contacts 106 and 107; then the circuit closer 121 is released and opens the 20 motor circuit at this point while it is still closed at the contacts 106 and 107. Consequently there is no sparking at the contacts 119, 120 due to the dropping down of the circuit closer 121, and the stopping of the motor is accurately timed by the 25 notches 104 in relation to the several sequences of the striking pins, 88.

To prevent the armature 115 dropping down too far and to set it to operate just right there is an 30 adjustable stop 136 provided beneath the armature and comprising a screw mounted at its lower end in a suitable screw-threaded hole in the shelf 113 and locked in adjusted position by a jamb nut 137.

It is to be noted that the end plate 36 is provided with a relatively large rectangular opening 138 near its top and opposite to the control mechanism through which the operation of the control mechanism can be observed and adjusted; this same opening serves in the end plate 35 40 in permitting the assembling of the motor and speed reducer with the frame work. The speed reducer 96 is mounted on an L-shaped bracket 139 secured to and extending inwardly from the end plate 35. The gear reducer is secured to the 45 bracket by screw bolts 140.

It might sometimes occur, either by accident or intentionally, that the push button 108 would not automatically release and open the control circuit before the motor circuit would be opened 50 by the opening of the circuit closer 107, and thus the apparatus might continue in operation for more than one sequence of sounds. To avoid such an occurrence I have provided an automatic circuit opener associated with the push button closer or any other means of temporarily closing the control circuit for starting the motor.

This automatic control circuit opener or protection device is designated generally by E, and is mounted on a shelf 141 of insulation material 60 arranged within the case substantially above the mechanism D. The shelf 141, as best shown in Fig. 3, is secured by an L-shaped bracket member 142, which in turn is rigidly secured to the upper frame bar 48. The various parts of the protecting device are secured to this shelf as to a base. These parts include, as best shown in Figs. 2, 5 and 6, a pair of resilient circuit controlling arms 143 and 144 provided with opposed contact points 145 and 146, respectively. The 65 arm 143 is rigidly mounted, at the end 147 opposite to the end which carries the contact point 145, on a bracket member 148 which is rigidly mounted on the shelf or base 141. The bracket 148 is U-shaped and one arm 149 thereof is secured to the base 141, as by screws 150. The

other arm 151 extends horizontally above the base 141 and is bent up at its free end 152 to form a stop to limit the downward movement of the resilient arm 143 when relieved of the pressure of the arm 144. The resilient arm 143 is secured at its rear end upon the rear part of the arm 151, as by a screw 153. A circuit wire is connected to the bracket 148 by one of the securing screws 150 and the contact point 145 is connected through the bracket 148 and resilient 10 arm 143 with said circuit.

The opposite arm 144 is one arm of a bell-crank the other arm 154 thereof projecting downwardly. The bell-crank, is pivotally mounted at its heel, to swing up and down, on a rigid bracket 155, secured to and standing up on the base 141, by a pivot screw 156.

As best shown in Fig. 6, the bracket 155, is secured to the base 141 by a bolt 157 and by a screw 158. The bolt 157 passes through the base 20 141 and serves to connect the other circuit wire so that when the two contact points 145 and 146 are in contact the circuit is closed at this point.

A tension spring 159 is connected at one end to the dependent arm 154 of the bell-crank and at its other end to a rigid L-shaped bracket 160, which is secured rigidly to and stands up on the base 141, and the spring tends to swing the contact arm 144 downwardly and break the circuit. For holding the arms 143 and 144 in contact 30 against the pull of the spring 159 I provide a thermally controlled device which is heated when current passes through the circuit including the arms 143 and 144, and when heated functions to let the spring 159 pull the arms 143 and 144 35 apart and open the circuit. It should be noted that the free end 161 of the arm 144 projects beneath the arm 151 of the bracket 148 and is thus prevented from being swung too high by the protecting device. The arrangement of the 40 free ends of the arms 143 and 144 and the stop 152 is such that when the arm 144 is swung up to close the circuit the points 145 and 146 are brought into contact and both arms stand free of the bracket arm 151, as best shown in Fig. 2. 45

The thermally controlled device includes a very fine wire 162 which is tensioned around a spool 163 of insulation material. The spool 163 is rigidly mounted in connection with the bell crank lever 144—154 by means of a rigid dependent projection 164, which has a screw-threaded opening adapted to receive a screw 165 which passes through a central hole in the spool and clamps the spool between the head of the screw and the lower end of the projection 164.

The spool 163 has a central circumferential 55 groove 166 which receives the thermal wire 162. The wire 162 is stretched in U-form and each end of the wire is secured to a small rod 167 by which the wire can be secured in stretched condition. The rods 167 are clamped in binding posts 168 which are mounted on and rise from the base 141, one at each side of the bracket 148. These posts are connected in the circuit and when the circuit is closed the wire is heated and expands in length and allows the spring 159 to open the circuit at the points 145, 146.

Beneath the base 141 there is provided a simple rheostat 169 which is in circuit and by which the amount or proportion of current passing through 70 the thermal control wire 162 can be regulated in an obvious manner. The rheostat 169 is of the bare wire type and a swinging adjustable contact lever 170 is provided which is adapted to be swung over and in contact with the rheostat 75

winding to cut in more or less of the wire of the rheostat as may be required, due to a variation of voltage, to cause the protector E to properly function. The tension of the thermal wire 162 is adjusted by loosening the binding screw in one of the binding posts 168, pulling on the rod 167 to produce the tension required and tightening the binding screws again. The wire 162 should be so tensioned, when cold, that the contact arm 143 is lifted free of the stop 152 and the free end of the opposite arm 144 is against the lower side of the end 161 of the bracket 148.

The circuit in which the control device E and the relay 111 are included is what may be termed the low voltage or control circuit and includes the various means for manually or automatically closing this circuit for effecting the starting of the motor C in the manner that has been described.

Besides the ordinary push button 108 before referred to, I also illustrate a circuit closer which, in its operation, closes the control circuit for but an instant, but the relay mechanism D is so sensitive that even such an instantaneous closing of the control circuit effects the starting of the motor and the operation of the apparatus through one cycle of sounds. Such a circuit closer is illustrated at 109, (see Fig. 22).

This circuit closer 109 consists of two contact levers 172 and 173 provided with opposed contact points 174 and 175 respectively. The lever 172 is rigidly mounted on a base 176 which is adapted to be secured to the top 177 of a door frame. The lever 173 is a swinging lever and is pivotally mounted at its upper end to swing up and down on the free end of a bar 178 which is likewise secured at one end to the base 176. The lever 173 hangs in the path of the top of a door 179 and the arrangement is such that when the door is closed by being swung to the right, Fig. 22, the dependent lever 173 swings freely to the right to allow the door to pass and as the door closes the lever drops down into the path of the door. As the door is moved to the left, Fig. 22, to open it the lever 173 is swung to the left and effects the closing of the contacts 174, 175, thus closing the control circuit. If the door is swung open very quickly the contacts 174 and 175 maintain the control circuit closed at this point for a very short time, but even so the motor C is started and the apparatus functions as described, due to the relay D instantly locking the motor into circuit by means of retaining latch 128 and 129.

I have illustrated still another means for starting the motor, that is, in connection with the clock 31.

As shown in Fig. 12 the clock 31 is provided with a circuit closer 110. This closer comprises a pair of contact levers 180 and 181 rigidly mounted on an insulation base 182. The lever 180 is provided with a block 183 of insulation material secured on its free end. The clock is provided with an alarm latch which is normally in position to engage the lower end of the block 183 and hold the lever 180 up out of contact with the other contact member 181.

When the clock operates to release the control lever and allow the alarm to sound the wedge shaped end 184 is swung out from its circuit open position to a position shown at 185, thus allowing the resilient lever 180 to close down into contact with the lever 181 and thus close the motor circuit.

It does not appear to be necessary to more fully describe the alarm clock mechanism, as the par-

ticular arrangement of the circuit closing levers 180 and 181 and the means for permitting them to close the motor circuit will depend upon the type of alarm clock used.

Suffice it to say that I prefer to arrange the 5 clock control independent of or not effected by the protective device E, as it is desirable to provide such a means of stopping the motor, when started by a clock, as will necessitate manual manipulation.

10

Such a means is shown and consists of a hand switch or circuit opener 186 arranged in circuit with the clock circuit closer 110. Thus when the switch 186 is open the clock will not cause the apparatus to function. When the switch is closed, 15 the clock will cause the apparatus to sound at the time indicated by the setting of the alarm, indicated by the hand 32, and the apparatus will continue to operate and proceed with a succession of sequences of sound for a long duration, 20 unless the operation is manually stopped by the opening of the switch 186.

Having now fully described the several devices and their functions I will proceed to explain in detail the several circuits and their co-operating 25 arrangements by means of the diagram shown in Fig. 22.

In said Fig. 22, the motor circuit is shown as having a source of supply at 187. One conductor 188 leads to the motor C. A conductor 189 leads 30 from the motor C to the control mechanism D which includes the starting closer 119, 120, 121 etc. and a conductor 190 leads from the control mechanism D back to the other side of the supply. It will be clear that the starting closer 119, 120, 35 121 etc. is in parallel with the circuit controlled by the notched control wheel 55 and when the motor circuit is started by the operation of the relay device the wheel 55 commences to rotate and effects the closing of the motor circuit before 40 it is opened by the dropping of the closer element 121.

It will also be clear that, as shown, when the wheel 55 has made a third of a revolution, the motor circuit will be opened and the motor will 45 stop.

The source of supply for the starting or control circuit 191 as shown is preferably a power circuit 192 through a transformer 193 which reduces the voltage to one suitable to use on a push button or 50 bell circuit, that is to approximately 10 volts.

As shown in Fig. 22 one conductor 194 leads to the push button 108, and a branch, as shown at 195, leads to the door operated circuit closer 109. The other conductor 196 from the supply 191 leads 55 first to the relay 111 and then back through the protector E and conductor 197 to the push button 108 and by the conductor 198 to the door closer 109.

The circuit opening members 143 and 144 are interposed in this return conductor and the thermal wire 162 is in a shunt circuit to this control circuit, so that when the circuit is closed either by the push button 108 or door closer 109 current will flow through the wire 162, thus heating it, 60 and if the circuit remains closed longer than a predetermined time it will be automatically opened by the separation of the members 143 and 144 and therefore, no matter how long the control circuit remains closed, the apparatus will 65 only operate through one cycle as defined by the notches in the control wheel 55.

The clock circuit closer is of a different character and is preferably independent of the control mechanism E. The coil of the clock 31,

which is preferably an electrically operated self starting clock, is connected by the conductor 199 on one side with conductor 188, of the motor supply through two co-operating contacts 200 and 201 carried by the clock case and the frame of the apparatus respectively and adapted to be brought into contact with each other when the case 30 is secured in place on the apparatus.

The other side 190 of the supply is connected to the clock coil by the conductor 202 and the alarm control circuit, that is the contacts 180 and 181 are connected to one side of the supply 190, as shown at 203, and the other side of the control circuit is first connected to the switch 186 and then to the other side 188 of the supply by the conductor 204, through a third pair of contacts similar to the contacts 200 and 201.

As thus connected, when the alarm clock operates to close the contacts 180 and 181, the clock switch 186 being closed, the motor circuit will be closed through 188, 189, 204, 186, 181, 180 and 202, and the apparatus will continue to operate until the switch 186 is manually opened.

As many modifications of the invention will readily suggest themselves to one skilled in the art I do not limit or confine the invention to the specific details of construction and operation nor to the specific combinations of associated devices and constructions except within the scope of the appended claims.

I claim:—

1. In an apparatus of the kind described, a sound device, a hammer for hitting the sound device, a rigid hammer arm, a fixed shaft upon which the hammer arm is pivotally mounted to swing from and toward the sound device, means for yieldingly holding the hammer arm in a normal position with the hammer spaced from the sound device, resilient means by which the hammer is mounted on the hammer arm to swing therewith, means for releasing the hammer arm and permitting the yielding holding means to swing the hammer arm toward the sound device, a stop in the path of the swinging hammer arm arranged to stop the striking movement of the hammer arm at a point where the hammer is spaced from the sound device, the arrangement being such that the resilient mounting of the hammer permits the hammer to strike the sound device and effects its instant withdrawal from the sound device to its normal position, and the stop being adjustable in the path of the hammer arm for varying the normal spacing of the hammer from the sound device.

2. In an apparatus of the kind described, a sound device, a hammer for hitting the sound device, a rigid hammer arm, a fixed shaft upon which the hammer arm is pivotally mounted to swing from and toward the sound device, means for yieldingly holding the hammer arm in a normal position with the hammer spaced from the sound device, resilient means by which the hammer is mounted on the hammer arm to swing therewith, means for releasing the hammer arm and permitting the yielding holding means to swing the hammer arm toward the sound device, a hammer stop carried by the fixed shaft arranged to stop the striking movement of the hammer arm at a point where the hammer is spaced from the sound device, the arrangement being such that the resilient mounting of the hammer permits the hammer to strike the sound device and effects its instant withdrawal from

the sound device to its normal position, the hammer stop comprising a yoke surrounding the pivoted end of the hammer arm and mounted on said shaft, and means for rigidly fixing the yoke on the shaft and permitting the adjustment of the yoke on the shaft to regulate the spacing of the hammer from the sound device.

3. In an apparatus of the kind described, a sound device, a hammer for hitting the sound device, a rigid hammer arm, a fixed shaft upon which the hammer arm is pivotally mounted to swing from and toward the sound device, means for yieldingly holding the hammer arm in a normal position with the hammer spaced from the sound device, resilient means by which the hammer is mounted on the hammer arm to swing therewith, means for releasing the hammer arm and permitting the yielding holding means to swing the hammer arm toward the sound device, a stop for the hammer arranged to stop the striking movement of the hammer arm at a point where the hammer is spaced from the sound device, a stop member rigidly mounted on the fixed shaft and upon which said stop is carried, the arrangement being such that the resilient mounting of the hammer permits the hammer to strike the sound device and effects its instant withdrawal from the sound device to its normal position, and said stop member being adjustable around said shaft for changing the normal spacing of the hammer from the sound device.

4. In an apparatus of the kind described, a sound device, a hammer for hitting the sound device, a rigid hammer arm, a fixed shaft upon which the hammer arm is pivotally mounted to swing from and toward the sound device, means for yieldingly holding the hammer arm in a normal position with the hammer spaced from the sound device, resilient means by which the hammer is mounted on the hammer arm to swing therewith, means for releasing the hammer arm and permitting the yielding holding means to swing the hammer arm toward the sound device, a rigid hammer stop carried by the fixed shaft arranged to stop the striking movement of the hammer arm at a point where the hammer is spaced from the sound device, the arrangement being such that the resilient mounting of the hammer permits the hammer to strike the sound device and effects its instant withdrawal from the sound device to its normal position, a yoke surrounding the pivoted end of the hammer arm, the rigid hammer stop being carried by the yoke, the yoke being capable of being adjusted around the shaft for varying the normal distance of the hammer from the sound device, and a cushion interposed between the hammer arm and the rigid hammer stop.

5. In a chime mechanism of the kind described, a hammer assembly comprising a fixed shaft, a hammer arm, a hammer resiliently mounted on the hammer arm, the hammer arm having a hub for pivotally mounting the hammer arm on the fixed shaft, a yoke having spaced hubs between which the hub of the hammer arm is received, means for fixing the yoke on the fixed shaft, the hammer arm and the yoke having cooperating projections by which the normal position of the hammer can be fixed, means for displacing the hammer arm, and means for returning the hammer arm to normal position when it is displaced.
